UNITED STATES PATENT OFFICE.

HIRAM RICHARD DE LAYE, OF BIRMINGHAM, ALABAMA.

FOLDING CRATE.

1,191,067.

Specification of Letters Patent.

Patented July 11, 1916.

Application filed September 19, 1913. Serial No. 790,719.

To all whom it may concern:

Be it known that I, HIRAM RICHARD DE LAYE, a citizen of the United States, residing at Birmingham, in the county of Jefferson and State of Alabama, have invented new and useful Improvements in Folding Crates, of which the following is a specification.

This invention relates to folding crates and it consists in the novel features herein-after described and claimed.

An object of the invention is to provide a crate as indicated which consists of parts adapted to be folded in close relation in order that the crate may occupy but little space during transportation or storage.

With the above object in view the structure includes a bottom provided at its side edges with longitudinally disposed strips. Side panels are pivotally connected with the strips and are provided with grooves which register with grooves provided at the inner sides of the strips. Said side panels are provided with threaded studs located at the inner surfaces of the panels. End panels are adapted to be received in the grooves of the said parts when the crate is set up and a top piece is provided with openings adapted to receive the studs. Nuts are screwed upon the studs and hold the parts in proper position.

In the accompanying drawing:—Figure 1 is a perspective view of the crate showing the parts in set up position. Fig. 2 is a horizontal sectional view of the crate. Fig. 3 is a longitudinal sectional view of the same. Fig. 4 is a transverse sectional view of the same. Fig. 5 is a transverse sectional view of the crate showing the parts collapsed and secured. Fig. 6 is a perspective view of a portion of the crate.

The crate includes a bottom 1 having at its side edges upstanding strips 2. Side panels 3 are hingedly connected at their lower edges with the upper edge portions of the strip 2 and the said panels 3 are provided at their inner sides with grooves 4 which register with grooves 5 provided at the inner sides of the strips 2. Threaded studs 6 are secured to the inner surfaces of the side panels 3 and nuts 7 are screwed upon the upper end portions of the said studs. End panels 8 are adapted to be received in

the grooves 4 and 5 of the panels 3 and strips 2 when the crate is set up. A top panel 9 is provided in the vicinity of its corners with openings 10 adapted to receive the upper portions of the studs 6 when the crate is set up. The panels 3 and 8 and the top 9 are in the form of open frames which are covered with wire netting of any desired mesh. The top panel 9 is provided with hinged or slidable door sections 11. The bottom 1 is provided in the vicinity of its center with openings 12 through which wire or cord may be passed for the purpose of holding the parts when collapsed.

When the parts of the crate are in set up position the crate may be used for transporting poultry and when it is desired to return the crate the nuts 7 are removed from the ends of the studs 6. The end panels 8 are then slipped out of the grooves 4 and 5 and are laid upon the bottom 1 between the strips 2. The nuts 7 are then replaced upon the studs 6 and the side panels 3 are swung down over the end panels which are placed upon the bottom 1. The top 9 is then placed over the swung down side panels 3 and a wire or cord is threaded through the openings 12 and through the end panels 8 and the ends of the said wire or cord are secured together. As shown in Fig. 5 a wire or cord may be placed around the structure when the parts are collapsed.

Thus the parts when in knocked down position are held in compact form for reshipment. Therefore it will be seen that a knock down crate of simple and cheap structure is provided and that the parts effectually coöperate with each other to brace the entire structure when the same is in set up condition.

Having described the invention what is claimed is:

A folding crate comprising a bottom provided at a point within its edges with an opening adapted to receive a securing device, strips secured to two of the opposite edges of the bottom and provided at their inner sides with grooves, side panels hingedly connected with the strips and provided at their inner sides with grooves which register with the grooves in the strips, end panels adapted to slidably fit in the said grooves, the combined thickness of

both of the end panels being equal to the vertical height of the strips, studs fixed on the side panels and movable with the same, and a top panel having openings adapted to receive the studs and provided with an intermediate screen section, and means for securing the top panel upon the studs.

In testimony whereof I affix my signature in presence of two witnesses.

HIRAM RICHARD DE LAYE.
